3 Claims. (Cl. 250—27.5)

1

This invention relates to a device comprising a current converting tube having a filling of gas or of vapour or of both, in which a cathode-screen is provided between the cathode and one or more anodes.

These tubes often have the drawback that the first ignition voltage required when placing the tube into service, largely depends on the temperature. When, for instance, just after the operation the tube is practically still at its operating temperature, the first ignition voltage required on operating the tube anew is very high. When as a result of screens placed between the cathode and the anode the discharge has to follow complicated paths the requirement of an increased ignition voltage in the case of a high temperature of the tube is particularly manifest.

Tubes that are so constructed as to be free from arcing back at the full operating voltage and at every cathode temperature lower than the normal (Application for a patent Serial No. 731,289, filed February 27, 1947, now Patent 2,452,861 issued November 2, 1948) switched on simultaneously with the heating current.

It is already known to connect a screen, which is placed between cathode and anode, to one of the anodes through a resistance. This, however, has the drawback of the full voltage being set up between this screen and the cathode in the negative phase, which may involve a very strong glowing current between these electrodes.

The present invention purports to cure these drawbacks by connecting the cathode screen of the tube to a potentiometer or voltage-divider connected between the cathode and one of the anodes. The current from the cathode to the screen ionizes the gas at a comparatively low voltage which depends on the filling of the tube. Once the current from the cathode to the screen has ionized the gas medium, charge carriers readily enter the range of the anode field in substantial quantity. In practice the paths of the gaseous medium to the screen and anode are ionized simultaneously. The choice of the point of a voltage-divider, where the cathode screen is connected, determines the anode voltage at which ionization occurs. Of course, the resistance of the voltage-divider between the anode and the screen should not be too low in order to prevent an unduly strong glow discharge between cathode and screen in the negative phase.

Although, once the tube gas medium has ionized and conveys a little current, re-ignition takes place very easily tubes having two and more anodes suffer from the drawback that the conditions of re-ignition are not the same for all

2

anodes, due to the fact that the cathode screen is connected between one of the anodes terminals and the cathode. In this case it is particularly advantageous to connect a certain number of parts of the cathode screen corresponding to the number of anodes to the voltage divided connected between the cathode and each anode.

It is particularly advantageous to use the invention in tubes for more than 100 volts effective anode voltage and at least 10 amperes rectified current, in which the screens between the cathode and the anodes are provided in such a manner that at the full operating voltage the tube does not exhibit arcing back at every cathode temperature lower than the normal.

In a special form of construction of these tubes the cathode screen or parts thereof are provided with holes on the side facing the one or more anodes, which holes do not serve for the passage of the main discharge and therefore do not amount to more than 5% of the aperture distant for the last-mentioned discharge, in such a manner that particles disintegrating from the cathode cannot find their way to the anodes. By providing the ignition holes it is ensured that charge carriers from the space with the cathode screen can easily enter the range of the anode field between anode and screen.

In one form of construction of a tube which particularly satisfies the requirement of freedom from arcing back, the terminal wires of the cathode and the one or more anodes are surrounded by tubes of ceramic material which are fused together with the wall of the tube, whereas the anodes, except for the active front surface, are surrounded by a screen consisting of conductive material, preferably metal gauze, which is secured to the tubes protecting the terminals. Between the anodes is placed a screen consisting of metal sheet whose rounded front side is closed to the cathode screen, the screens being arranged about the cathode in such manner that particles, for instance of electron-emitting material, issuing from the cathode do not have a velocity component in the direction of the anode even after a reflection.

The current converting tubes that are the object of the present invention often have at the bottom side a metal hood for taking up the stock of vapor-producing material, usually mercury. Sometimes the metal hood is advantageously furnished with cooling ribs in order to maintain the temperature of the mercury as low as possible. It is particularly simple and cheap to mount the resistances of the voltage-divider on the cooling ribs, so that the user of the tube need not bother

about these parts and may connect the tube in the same manner as tubes without cathode screen or those where the cathode screen is internally connected to the cathode.

In order that the invention may be clearly understood and readily carried into effect it will now be described more fully with reference to the accompanying drawing, given by way of example.

Figures 1a, 1b and 1c are of vertical section, a bottom view and a horizontal section respectively of a tube having two anodes, in which the cathode screen is connected through a voltage-divider to one of the anodes, Figures 2a, 2b and 2c being respectively a vertical and a horizontal section of the cathode screen of the tube, in which the cathode screen is divided into two parts, and a bottom view of this tube.

The current converting tube shown in Figure 1 comprises a glass discharge vessel 1, in which the cathode 2 and the anodes 3 are provided in the same way by means of terminal wires 4 and 5 which, through the intermediary of chrome iron hoods 6 and 7 are sealed in a vacuum-tight manner into the ends of the tube. Each anode is surrounded by a screen 8 partly consisting of metal gauge and shielding the inactive part of the anodes. The terminal wires are surrounded by the ceramic protecting tubes 9 and 10 which are fused together with the glass wall at the anode inlet 11. Between the anodes is placed a flat screen 12 having a rounded front side and being secured to the tube 10 of the anodes protecting the terminals. The cathode is surrounded by a screen consisting of a cylindrical part 13, which is closed at the bottom side, and a flat part 14 whose edge is bent over. The cathode screen 13, 14 is connected to the inlet 15 through the intermediary of a connecting wire 28. The two cathode inlets are furnished with copper connecting leads 16. At the bottom side of the tube is provided a chrome iron hood 17 containing the stock of mercury 18 which is protected by the screen 19 from the thermal radiation from the tube. The chrome iron hood 17 has secured to it a cooling rib 20 by which it is ensured that the temperature of the mercury 18 only slightly exceeds room temperature. On the rib 20 are mounted two resistances 21 and 22 jointly constituting the voltage-divider between the cathode and one of the anodes. The resistance 21 is directly electrically connected to the rib 20. The resistance 22 is insulated from the rib 20 by means of two insulating plates 23. A wire 24 connects the two resistances to the inlet 15 of the screen. The wires 26 and 27 are connected respectively to the centre of the heating winding of the supply for the device comprising the current-converting tube and to one of the anode terminals of the tube. The nuts 25 serve to secure the resistances and the connecting wires. The cathode screen is provided with four ignition holes 29 by which the ignition of the anode current is facilitated. Besides a filling of mercury the tube also has a filling of argon under the pressure of 0.7 mm. The resistance 21 has a value of 10,000 ohms and the resistance 22 of 20,000 ohms. The screen path of the gaseous medium ionized at about 10.5 volt. Since the anode path of the gaseous medium and the screen path of the gaseous medium ionize practically simultaneously, ionization occurs at a voltage of 32 independently of the temperature. The tube is designed for an alternating anode voltage of 220 effective. Of course, the two volt-

divider resistances may be given different ratio so that the ionization occurs at a different anode voltage.

In Figure 2 the parts corresponding to Figure 1 bear the same reference numerals as in Figure 1. In this case the cylindrical part of the cathode screen is divided into two parts 13' each of which corresponds to one of the two anodes and is secured to a terminal protecting tube of the cathode. The two halves 13' slightly overlap each other so that disturbances on account of electron emitting material disintegrating from the cathode are avoided. The cover 14 of the cathode screen is separately secured to the insulating terminal tubes.

The tube includes two inlets 15 for the two parts of the cathode screen and as further shown in Figure 2C two potentiometers each made up of a resistor pair 21—22 are provided. The voltage-divider is also constructed double and the chrome iron hood 17 is centrally positioned.

What I claim is:

1. A gaseous discharge current converting tube comprising a closed vessel having a gaseous filling, and containing a cathode, a plurality of anodes, and a cathode screen mounted between the cathode and the anodes, the cathode screen having a number of sections corresponding to the number of anodes, a voltage-divider connected between the cathode and each anode, and means connecting each cathode screen section to an intermediate point of the corresponding voltage-divider between the cathode and the associated anode.

2. A gaseous discharge tube comprising a closed vessel having a gaseous filling, and containing a cathode and an anode, conducting supports for the cathode extending through the wall of the vessel and into the inner space in the vessel, insulating tubes covering the supports to substantially the terminals of the cathode, a cathode screen substantially enclosing the cathode, means supporting the cathode screen on the insulating tubes and insulated from the cathode, and potentiometer resistance means interconnecting said anode, cathode and cathode screen for maintaining the potential of the cathode screen at a value between the potentials of the cathode and of the anode.

3. A gaseous discharge current converting tube comprising a closed vessel having a gaseous filling, and containing a cathode, an anode and a screen for the cathode, a metallic cup secured in the base of the tube to communicate with the tube, a globule of mercury in the cup, heat radiating ribs attached to the cup, resistance means supported on said ribs, and an electrical conductor extending through the base of the tube with its inner end connected to the cathode screen and having an external terminal for connection to a point on the resistance means.

Certificate of Correction

January 18, 1949.

JOHANNES GIJSBERTUS WILHELM MULDER

It is hereby certified that errors appear in the printed specification of the above numbered patent requiring correction as follows:

Column 1, line 5, for the word "anode" read *anodes*; line 23, after the parenthesis and before "switched" insert *exhibit a very great dependency of the ignition voltage on the temperature. In these tubes the anode voltage may be*; line 40, for "gas" read *gaseous*; column 2, line 6, for "divided" read *divider*; column 3, line 27, for "gauge" read *gauze*; line 69, for "ionized" read *ionizes*;

and that the said Letters Patent should be read with these corrections therein that the same may conform to the record of the case in the Patent Office.

Signed and sealed this 24th day of May, A. D. 1949.
